United States Patent Office

Des. 195,203
Patented May 14, 1963

195,203

120 COLUMN PRINTER ENCLOSURE

Charles E. Bozarth, Phoenix, Ariz., assignor to General
Electric Company, a corporation of New York

Filed Apr. 10, 1961, Ser. No. 64,663

Term of patent 14 years

(Cl. D26—5)

Fig. 1

Fig. 2

FIG. 1 is a perspective front three quarter view of a 120 column printer enclosure, showing my new design.

FIG. 2 is a perspective rear three quarter view of same.

I claim:

The ornamental design for a 120 column printer enclosure, as shown.
